UNITED STATES PATENT OFFICE.

ANDREW G. SANDBERG, OF ST. PAUL, MINNESOTA.

TRIPLE-VALVE-TESTING RACK.

SPECIFICATION forming part of Letters Patent No. 772,378, dated October 18, 1904.

Application filed March 5, 1904. Serial No. 196,644. (No model.)

To all whom it may concern:

Be it known that I, ANDREW G. SANDBERG, a citizen of the United States, residing at St. Paul, in the county of Ramsey and State of Minnesota, have invented certain new and useful Improvements in Triple-Valve-Testing Racks; and I do hereby declare the following to be a full, clear, and exact description of the invention, such as will enable others skilled in the art to which it appertains to make and use the same.

My invention has for its object to provide a simple, efficient, and quickly-acting clamping device for clamping triple valves to testing-racks and for coupling thereto the air-supply hose or tube.

To the above ends the invention consists of the novel devices and combinations of devices hereinafter described, and defined in the claims.

Hitherto it has been customary to test triple valves of air-brake systems in the shop in connection with testing-racks involving an auxiliary reservoir, brake-motor, and co-operating parts. The common practice has been to connect a triple valve to the auxiliary reservoir of the testing-rack by means of nuts and bolts and to connect the air-supply pipe or hose to the receiving-neck of the triple valve by a suitable coupling. These operations have consumed a very considerable time and are not always satisfactorily accomplished by these old devices.

By means of my improved clamping device I very quickly and simultaneously clamp the triple valve to the auxiliary reservoir of the rack and couple the air-hose to the receiving-neck of the triple valve.

The invention is illustrated in the accompanying drawings, wherein like characters indicate like parts throughout the several views.

Figure 1 is a view in side elevation with some parts broken away and with some parts sectioned, showing a triple valve clamped to the auxiliary reservoir of the rack and connected with the air-supply hose by my improved clamping device. Fig. 2 is a quite similar view to Fig. 1, but illustrates different positions of the parts; and Fig. 3 is a

transverse vertical section taken approximately on the line $x^3 x^3$ of Fig. 2.

The numeral 1 indicates the floor or other base-support for the rack, from which an auxiliary reservoir 2 and a connected brake-cylinder 3 are supported by a pair of stands 4.

The numeral 5 indicates an ordinary triple valve having a receiving-neck 6 at its lower portion and having at one end a flange 7, the face of which when the triple valve is coupled to the auxiliary reservoir engages and closely fits a projecting end portion 8 of the said reservoir.

The numeral 9 indicates a vertically-disposed spring bar or standard which is secured at its lower end to the base-support 1 and is provided with a forwardly-projecting clamping-arm 10. A hose-coupling 11 projects through and is secured to the free end of the clamping-arm 10. The air-supply hose 12 is permanently attached to the outwardly-projecting end of the coupling 11, and the said coupling at its inwardly-projecting end is formed with a nozzle 13, which is adapted to fit with an air-tight joint into the receiving-neck 6 of the triple valve. Normally the spring-standard 9 and its arm 10 stand as shown in Fig. 2, in which position the nozzle 13, it will be noted, stands out of engagement with the receiving-neck of the triple valve. The said standard and arm therefore afford an oscillating support for the nozzle or hose-coupling.

The numeral 14 indicates a pronged lever, the prongs of which are pivoted at 15 to the sides of the auxiliary reservoir 2. The prongs of said lever 14 at their upper free ends are connected by links 16 to a transversely-extended clamping-bar 17, which bar is adapted to engage the upper portion of the triple-valve flange 7 in a manner illustrated in Fig. 1 and hereinafter more fully described. Nuts 18 on the ends of the links or rods 16 afford means for adjusting the clamping-bar on the said clamping-rods.

A crank-shaft 19 is mounted in bearings 20 on the upper end of the spring-standard 9 and is provided with a crank 21, which works between said bearings and through a slot 22,

cut in the said standard. At one projecting end the crank-shaft 19 is provided with a lever 23, by means of which it may be readily moved, and it is also provided with a cam-lug 24 for a purpose which will presently appear.

A pair of rods 25, which extend on opposite sides of the lower portion of the positioned triple valve, connect the upper ends of the 10 spring-standard 9 and spring-arm 10, said rods being provided at their ends with nuts 26. A swiveled block 27 connects the lower ends of the members which make up the forked lever 14. A plunger or crank-rod 28, pivoted at 15 one end on the crank 21, works through the block 27 and at its projecting end is provided with a nut 29. A coiled compression-spring 30 on the projecting end of the rod 28, compressed between the block 27 and the nut 29, 20 yieldingly draws said rod to its limit through the said block.

Pivoted at its intermediate portion to one side of the forward standard 4 is a lever 31, which at its rear end is connected by a link 32 to the intermediate portion of one of the 25 clamping-rods 16. The free forward end of this lever 31 is normally engaged by the cam-lug 24 of the crank-shaft 19.

What will be treated as the normal positions of the parts of the clamping device are 30 illustrated in Fig. 2. Normally therefore it will be seen that the cam-lug 24, acting on the lever 31 and through the link 32, holds the clamping-bar 17 raised out of the way of 35 the valve, and the spring-arm 10 holds the hose-nozzle 13 out of engagement with the neck 6 of the triple valve, so that the said triple valve may be freely placed in working position or removed therefrom. The triple 40 valve being placed in working position, as shown in Fig. 2, the lever 23 is thrown upward, as shown in Fig. 1. This upward movement of the lever first carries the cam-lug out of action on the lever 31, and thus causes the 45 clamping-bar 17 to be lowered into position to engage the upper portion of the triple-valve flange 7. The continued upward movement of said lever throws the crank 21 of the shaft 19 slightly upward of or beyond its dead-center 50 with respect to the crank-rod 28. This movement of the said crank very materially compresses the spring 30 on the crank-rod 28 and draws the spring-arm 10 toward the triple valve, thereby forcing the nozzle 13 into tight 55 engagement with the neck 6 of said triple valve. Otherwise stated, the said movement of the crank tends to shorten, and does, in fact, shorten, the distance between the free end of the arm 10 and the lower end of the lever 14, 60 and the base of reaction in the one instance is against the nozzle 13 and in the other is against the clamping-bar 17. Thus the entire clamping force is applied to clamp the triple valve to

the auxiliary reservoir and the said nozzle 13 to the neck of the triple valve. This force 65 may be varied considerably by adjustments of the tension of the spring 30. It will thus be seen that by a single movement of an operating-lever the triple valve is clamped in working position on the rack and is coupled 70 to the air-supply hose. It of course follows that the valve is disconnected from the rack by a reverse movement of said operating-lever.

From what has been said it will of course be understood that the device described is 75 capable of a great many modifications within the scope of my invention as herein set forth and claimed.

What I claim, and desire to secure by Letters Patent of the United States, is as follows: 80

1. The combination with a triple-valve-testing rack, of means for connecting a triple valve thereto, comprising a pair of valve-engaging members, intermediate lever connections mounted to move with respect to the 85 rack and connected to the said two valve-engaging members, for moving them to and from operative positions, on different portions of the valve, and an operating-lever applied to said connections for moving them at 90 will, substantially as described.

2. The combination with a triple-valve-testing rack, including an auxiliary reservoir, of a valve-clamping device comprising a clamp engageable with a portion of the triple valve 95 to press the same against the auxiliary reservoir, a nozzle engaging with the receiving-neck of said valve, a manually-operated crank, and lever connections from said crank to said clamp, and to said nozzle, arranged to react 100 against the said clamp and nozzle, in drawing them to working positions on said valve, substantially as described.

3. The combination with a triple-valve-testing rack, comprising an auxiliary reservoir to 105 which the triple valve is to be connected, of a manually-operated crank yieldingly supported, a spring-arm supporting a nozzle for engagement with the neck of the triple valve, a clamping-bar for engagement with a flange 110 on said triple valve, an intermediate lever connected to said clamping-bar, a crank-rod connected to said intermediate lever and to said crank, a connection between said crank and said nozzle-supporting arm, a cam-lug 115 connected to move with said crank, and lever connections to said clamping-bar subject to said cam-lug and arranged to lift said clamping-bar to and from an operative position, substantially as described. 120

In testimony whereof I affix my signature in presence of two witnesses.

ANDREW G. SANDBERG.
